J. R. Bryant.
Attorney

UNITED STATES PATENT OFFICE.

JOSEPH LANGER, OF HAMMOND, INDIANA.

WALL CONSTRUCTION.

Application filed March 29, 1923. Serial No. 628,484.

To all whom it may concern:

Be it known that I, JOSEPH LANGER, a citizen of Poland, residing at Hammond, in the county of Lake and State of Indiana, 5 have invented certain new and useful Improvements in Wall Constructions, of which the following is a specification.

This invention relates to new and useful improvements in wall construction where- 10 in hollow blocks are employed.

An important object of the invention is to construct a building wall from blocks that are positioned in staggered relation to each other and provided with suitable means 15 for properly connecting the same.

A further object of the invention is to provide a building wall that is constructed so as to allow proper circulation of air within the same.

20 A further object of the invention is to provide a novel anchoring strip that is adapted to coact with a suitable binding agent for permanently connecting adjacent blocks.

25 Other objects and advantages of the invention will be apparent during the course of the following description.

In the accompanying drawing forming a part of this specification and in which like 30 numerals are employed to designate like parts throughout the same,

Figure 1 is an elevational view, partly in section, of a portion of a wall embodying this invention,

35 Figure 2 is a top plan view, partly in section, taken on line II—II of Fig. 1,

Figure 3 is a partly sectional view and partly end elevational view taken on lines III—III of Fig. 1,

40 Figure 4 is a perspective view of one of the building blocks embodying this invention, and

Figure 5 is a detail perspective view of the anchoring strip employed to coact with 45 a suitable binding agent for properly connecting the building blocks.

Referring to the accompanying drawing and particularly to Figs. 1 to 3 inclusive, there is shown a section of a building wall 50 that is formed from the various elements embodying this invention. In constructing a wall after this invention, a base is laid that consists of plastic channel blocks 1, which are constructed from any desired composition, and form a continuous channel 2 along their upper faces. These blocks are

placed end to end and are connected by any desired binding agent, but precaution must be taken to prevent obstructing the said channel. The blocks 3 are then laid in longitudinal rows upon this base strip with the blocks forming each row placed in staggered relation to the blocks forming the next adjacent row or layer.

Referring particularly to Fig. 4, it will 60 be seen that the building block 3 is provided with a pair of spaced openings 4 that extend perpendicularly through the said block between its top and bottom faces. There are further provided pockets or recesses 5 that are of dove-tail shape in cross section and formed in the upper and lower faces of the block and are positioned between the adjacent open ends of the openings 4, the said block being further provided with relatively small recesses or 70 pockets 6 that are also of dove-tail shape in cross section and formed in the top and bottom faces outwardly of the ends of the openings 4. The end walls of the block 80 are provided with spaced recesses or pock- 75 etes 7 that are provided for properly connecting the ends of the blocks when they are placed in assembled position to form the wall.

Referring particularly to Fig. 5 wherein 85 the anchoring strip is shown in detail, it will be seen that this strip is formed from a single piece of metal that has been cut at spaced intervals to form the lugs or tongues 8 that are properly connected by the central strip portion 9, the said lugs being alternately bent in opposite directions to angular positions in respect to the strip portion 9, as shown.

It will be seen by referring to Figs. 1 and 2 that in assembling the blocks 3 in staggered relation that the perpendicular openings 4 will properly align in the various blocks to form continuous wells that are interconnected at their extreme bottom ends by the channel-way 2 formed in the blocks 1, it being seen from this construction that a complete circulation of air will be provided through the entire wall structure. The various pockets or recesses 5, 6 and 7 are provided for receiving a binding agent that is employed to properly connect the various blocks, the anchoring strips being employed to coact with the said binding agent for acting as a reinforcing means. Upon examining the sectional portion of

Fig. 1 it will be seen that the dove-tail shaped pockets or recesses 6 in the face of one block will be positioned in vertical alinement with the dove-tail shaped pockets or recess 5 formed in the block positioned in the next adjacent layer or row and that the anchoring strips will extend transversely of these adjacent blocks and will project into the recesses formed in the same, the forming of these pockets or recesses of dove-tail shape in cross section being to provide better holding means for the binding agent placed within the same. As stated above the pockets or recesses 7 formed in the ends of the blocks are adapted for suitably connecting adjacent blocks, this being accomplished by placing binding agents therein.

It is to be understood that the form of this invention herewith shown and described is to be taken as the preferred example of the same, and that various changes in the shape, size and arrangement of parts may be resorted to without departing from the spirit of the invention or the scope of the subjoined claims.

Having thus described the invention, I claim:—

1. In a structure of the class described, a base strip, layers of blocks placed upon said strip, the said blocks each having recesses formed in its various faces, a binding agent placed within said recesses, and anchoring strips positioned within the recesses formed in adjacently positioned blocks to connect the same, the said anchoring strips each consisting of a single piece of metal cut to form tongues upon opposite edges with the said tongues bent alternately in opposite directions.
2. In a structure of the class described, a channelled base strip, layers of blocks placed upon said strip with the blocks of

each layer placed in staggered relation to the blocks of the adjacent layers, each of said blocks having an opening positioned inwardly from each of its opposite ends and extending between the upper and lower faces thereof, the openings in each block alining with the openings adjacent the abutting ends of the blocks in the layers thereabove and therebelow to form vertical wells the full height of the structure with the openings in the lower layer of blocks communicating with the channel in the base strip, to provide a continuous circulation of air within the wall, and means for connecting the adjacent blocks, said means consisting of recesses formed in the various faces of each block and adapted to coat in the various blocks for receiving a binding agent placed within said recesses, and anchoring strips positioned within the recesses formed in adjacently positioned blocks to connect the same, the said anchoring strips each consisting of a single piece of metal cut to form tongues upon opposite edges with the said tongues bent alternately in opposite directions.

3. A building block of the type described, comprising a body portion, said body portion having a pair of spaced openings formed therein and extending between the upper and lower faces of the same, said upper and lower faces having a relatively large dove-tail-shaped recess formed therein between the adjacent open ends of said openings, and a relatively small dove-tail-shaped recess formed laterally outwardly of each of said open ends, and the end faces of said block having spaced transversely extending recesses formed therein.

In testimony whereof I affix my signature.

JOSEPH LANGER.
